COMBINATION LOCK

George T. Mason, Glendale, Calif., assignor to
Alfred A. Nathanson, North Hollywood, Calif.

Application September 4, 1945, Serial No. 614,369

3 Claims. (Cl. 70—293)

1

This invention relates to locks, and more particularly to combination locks especially designed for safes, cabinets and similar containers.

An object of my invention is to provide a combination lock which is particularly adapted for use in conjunction with a child's coin bank or safe, in that it is of unusually simple and inexpensive design, but which is not necessarily limited to such use, since so long as it remains locked it positively prevents opening the container with which it is associated, and yet is so designed that its combination is not easily solved with the result that the contents of any container equipped with one of these locks are given a measure of protection from being tampered with by unauthorized persons considerably in excess of what would ordinarily be expected of so inexpensive a lock.

Another object of the present invention is to provide a toy coin bank or safe equipped with a combination lock incorporating the principles of the present invention and having a particular appeal for a child, inasmuch as it simulates the appearance of the conventional, so-called office safe.

The invention possesses other objects and valuable features, some of which with those enumerated will be set forth in the following description of the preferred embodiment of my invention illustrated in the drawings accompanying and forming part of the specification. It is to be understood that I do not limit myself to the showing made by said drawings and description, but that I may adopt variations of the preferred embodiment within the scope of my invention as defined by the claims.

Referring to the drawings:

Figure 1 is a view in front elevation of a toy bank or safe having a combination lock incorporating the principles of the present invention operatively installed in cooperative association therewith.

Figure 2 is a view in side elevation, the direction of view being indicated by the arrow 2 of Figure 1.

Figure 3 is a perspective view of the toy bank of Figures 1 and 2, this figure being partially broken away and shown in section to reveal the structural details of the combination lock.

Figure 4 is an enlarged detail view in perspective showing the operative portions of the combination lock in the respective positions assumed thereby when locked.

Figure 5 is a view similar to Figure 4 showing the parts moved to their respective unlocked positions.

As clearly shown in Figures 1, 2, and 3, the bank 6 with which the lock 7 of the present invention is operatively associated, is designed to simulate in appearance, but in miniature size,

2

the conventional office safe. It comprises a hollow cabinet, inasmuch as it is defined by a back wall 8, side wall 9, top and bottom walls 11 and 12, respectively, and a door 13 which may optionally be swung open to give access to the interior of the bank 6, or swung closed, as illustrated in Figures 1, 2, and 3, so that it occupies a position substantially in planar alignment with the front edges of the side walls 9 and top and bottom walls 11 and 12, respectively.

Whereas any suitable means for pivotally mounting the door 13 may be employed, the door 13 illustrated is mounted by a pair of axially aligned pintle pins 14 extending beyond the top and bottom edges of the door 13 and seated within sockets in the top wall 11 and the bottom wall 12. This type of hinge mounting for the door 13 has been employed in the bank of the present modification, inasmuch as every effort has been expended to keep the overall cost of this item at a minimum, so as to offer for sale a child's bank of very low cost.

The combination lock 7 comprises a disc 21 revolvably mounted on the inner face of the door 13 sufficiently closely adjacent the edge 22 of the door which is remote from its hinges 14, for the edge of the disc 21 to extend into a groove 23 in the inner face of the associated side wall 9. Because this arrangement of the disc 21 enables the peripheral edge of the disc to seat within the groove 23, that portion 24 of the side wall 9 which defines the outer edge of the groove 23 operates as a keeper behind which the disc 21 engages to lock the door 13 against moving from its closed position. However, the disc 21, which will be termed herein a "detent" disc inasmuch as it operates as a detent when positioned behind the keeper 24 to hold the door 13 closed, is provided with a plurality, preferably a pair, of notches 26 in its peripheral edge; and when the disc is turned to bring either one of its notches 26 into registry with the keeper 24, the door 13 is free to swing open. The detent disc 21 is carried by an axial shaft 27 which extends through and is free to turn with respect to the door 13. A knob 28 is rigid with the forward end of the locking shaft 27; and associated with the knob 28 and exposed to view on the outer face of the door 13 is a dial 29 having indicia 31 thereon, preferably in the form of calibrations 32 and numerals 33 associated therewith to assist in rotating the knob 28 so as to bring the detent disc 21 which is rigid with the inner end of its shaft 27 to selected position of rotational adjustment about the axis of the shaft 27.

A plurality of tumbler discs 36 also are revolvably mounted upon the inner face of the door 13 at angularly separated locations about the axis of the detent disc's shaft 27. Each of these tumbler discs 36 is provided with a notch 37 in its

edge; and the axes of the shafts 38 upon which the tumbler discs 36 are mounted, are positioned so closely adjacent the axis of the detent disc's shaft 27 that the circles within which the peripheral edges of the two tumbler discs 37 lie, intersect the circle within which the peripheral edge of the detent disc 21 lies. Accordingly, either the detent disc 21 must extend into the notch 37 of both tumbler discs 36, as illustrated in Figure 5, under which circumstances the detent disc 21 is free to rotate, or the tumbler discs 36 must extend into the notches 26 of the detent disc 21, as illustrated in Figure 4, under which circumstances the two tumbler discs 36 will be free to rotate, but the detent disc 21 will be securely locked against rotation and in that position wherein its edge is engaged securely behind the keeper 24, with the result that the door 13 is securely locked.

On the forward end of each of the tumbler shafts 38, a knob 41 is provided, and a dial 42 is associated with each knob 41, the dial 42 also preferably being provided with indicia 43 such as calibrations 44 and numerals 46 as in the case of the detent disc's dial 29. Assuming that the door 13 is closed, when the detent disc 21 is in the Figure 4 position, the edge of the detent disc 21 seats behind the keeper 24 and thus securely locks the door 13 against opening. Moreover, since the two tumbler discs 36 seat within the notches 26 in the peripheral edge of the detent disc 21, the detent disc 21 is securely retained in its locked position.

When it is desired to unlock the locking mechanism 7 and thus permit opening the door 13, the knob 41 associated with the two tumbler discs 36 should be rotated until the notches 37 on the two tumbler discs face toward the detent disc 21, whereupon the detent disc 21 then can be rotated until either one or the other of its two notches 26 register with the keeper 24 whereupon the door 13 may be swung open. However, unless the person so operating the knobs 41 and 28 is informed of the combination of numbers indicating the respective positions to which dials 43 and 29 should be turned, he will be unable to manipulate the knobs 41 and 28 so as to position the discs 36 and 21 in the manner which is necessary to release the locking mechanism. Moreover, since a plurality of tumbler discs 36 is employed, a person unauthorized to open the combination lock will be unable to solve the combination by feeling the knobs as they are turned. This follows from the fact that both tumbler discs 36 must be turned to their Figure 5 position, so that their notched sides face radially inwards towards the detent disc 21 before the detent disc can be turned. Otherwise, the operator might, by urging the knob 28 to rotate while he is turning one of the knobs 41, detect by feeling when the notch 37 of the tumbler disc 36 associated with that knob moves into registry with the detent disc 21. However, he will be unable to detect any difference in feeling of the knob 28 when one of the notches 37 comes into registry with the disc 21, because of the fact that the disc 21 is still held positively against rotation by the other tumbler disc 36.

Consequently, even though the combination lock 7 of the present invention is of very simple, and consequently, very inexpensive construction, it does offer a measure of protection which is adequate to justify the use of a lock constructed in accordance with the principles of the present

invention on safes, cabinets and other containers for relatively valuable articles.

I claim:

1. A combination lock for a closure movable with respect to a keeper comprising a detent disc carried by said closure in position for the edge of said disc to engage behind said keeper, said disc having a notch therein and being revoluble about its own axis to move its notch optionally into or out of registry with said keeper, and a tumbler disk revolvably mounted on said closure and having a notch therein into which the edge of said detent disc extends when said detent disc's notch is turned away from said tumbler disc, said tumbler disc extending into said detent disc's notch when said tumbler disc's notch is turned away from said detent disc to immobilize said detent disc with the notch of said detent disc out of registry with said keeper.

2. A combination lock for a closure movable with respect to a keeper comprising a detent disc carried by said closure in position for the edge of said disc to engage behind said keeper, said disc having a pair of notches therein and being revoluble about its own axis to move its notches optionally into or out of registry with said keeper, and a pair of tumbler discs revolvably mounted on said closure at angularly separated locations about said detent disc, each of said tumbler discs having a notch therein into which said detent disc extends when said detent disc is turned to withdraw its notches from said tumbler discs, and each of said tumbler discs extending into one of said detent disc's notches when that tumbler disc is turned to withdraw its notch from said detent disc whereby said detent disc is immobilized with its notches out of registry with said keeper.

3. A combination lock for a closure movable with respect to a keeper comprising a detent disc carried by said closure in position for the edge of said disc to engage behind said keeper, said disc having a plurality of notches therein and being revoluble about its own axis to move its notches optionally into or out of registry with said keeper, and a plurality of tumbler discs revolvably mounted on said closure at angularly separated locations about said detent disc, each of said tumbler discs having a notch therein into which said detent disc extends when said detent disc is turned to withdraw its notches from said tumbler discs, and each of said tumbler discs extending into one of said detent disc's notches when that tumbler disc is turned to withdraw its notch from said detent disc whereby said detent disc is immobilized with its notches out of registry with said keeper.
